BUILDER MECHANISM FOR SPINNING FRAMES

Lionel Desrosiers, Lachute Mills, Quebec, Canada,
assignor to Whitin Machine Works, Whitins-
ville, Mass., a corporation of Massachusetts

Application June 30, 1937, Serial No. 151,303

5 Claims. (Cl. 242—43.3)

This invention relates to builder mechanism for spinning frames and particularly to improvements in the type of builder mechanism disclosed in U. S. Patent No. 1,926,390 granted Sept. 12, 1933.

An important feature of the mechanism disclosed in said patent is a wind-back motion for returning the spindle rails to starting position and stopping the machine, ready for doffing, when the winding of the bobbins is completed. Commencement of this motion must be accurately timed to ensure successful operation. If the timing is too late the spindle rails will not be raised to the original starting position and will thus fail to engage and operate the switch which causes the machine to be brought to rest. The resulting continuation of the winding motion will cause surplus yarn to be incorrectly placed on the bobbins until the machine is brought to rest by an attendant. If the timing is too early this may result in sufficient overtravel of the rails in an upward direction to cause breakage of the switch or other parts of the mechanism.

Accidental changes in the timing of the wind-back motion under operating conditions are usually due to imperfect adjustment of the restraining or braking pressure exerted on the sliding clutch reversing shaft by the spring device provided for this purpose. If the braking pressure is excessive the shifting of the shaft to the wind-back position by the clutch reversing lever may be delayed sufficiently to cause late commencement of the wind-back motion. If the braking pressure is inadequate the reversing shaft may be prematurely shifted to the wind-back position or it may even assume a neutral position during movement of the reversing lever in either direction. If the reversing shaft comes to rest in the neutral position the worm shaft, which controls both the progressive lowering and the wind-back of the spindle rails, will be thrown out of action with the result that the yarn will be incorrectly wound on the bobbins during the period that this condition is permitted to exist. The shifting of the clutch reversing shaft to the starting position as the wind-back motion is completed may also be delayed if the braking pressure on the shaft is excessive. This, however, is not a very serious matter since the machine is brought to rest as the wind-back motion is completed.

In practice considerable difficulty is experienced in closely regulating the braking pressure on the clutch reversing shaft so that this pressure will always serve its intended purpose without

delaying the shifting of the shaft to the wind-back position.

With the foregoing in mind the object of the present invention is to provide simple and efficient means for preventing delays in the commencement of the wind-back motion due to the retarding action of the braking pressure applied to the clutch reversing shaft. This object is accomplished, according to a preferred embodiment of the invention, by the provision of an auxiliary clutch shifting device comprising a normally retracted, spring-actuated impact member arranged to be released at the proper instant to strike the clutch reversing shaft with sufficient force to overcome the retarding effect of the braking pressure and ensure rapid shifting of the shaft to the wind-back position.

The invention also contemplates the provision of releasable restraining means by which the automatic clutch shifting means is permitted to become effective to shift the clutches to the wind-back position only when the builder cam is revolved to a predetermined position in relation to the cam engaging roller of the builder lever, the selected position of the cam being preferably such that the shifting of the clutches to the wind-back position occurs when the rail shifting shaft of the building lever is idle. The best results are obtained when the shifting of the clutches to the wind-back position is timed to occur when the lowest point of the cam is passing over the cam engaging roller of the builder lever. This ensures that the cam will come to rest at the completion of the wind-back operation with its highest point engaging said roller so that, when the machine is started up again after the doffing operation, the initial movement of the spindle rails in response to rotation of the cam will be in a downward direction.

Proceeding now to a more detailed description reference will be had to the accompanying drawings—wherein

Fig. 1 is a side elevation of a builder mechanism equipped with an auxiliary clutch shifting device designed in accordance with the present invention. This view shows the various elements in the position which they occupy during the winding of the bobbins.

Fig. 2 is a view similar to Fig. 1 but showing the various elements in the position which they occupy during the operation of the wind-back motion.

Fig. 3 is a top plan view of the assembly appearing in Fig. 1.

Fig. 4 is a detail view, partly in section, show-

ing the mounting of the spring device by which the restraining or braking pressure is applied to the sliding clutch reversing shaft.

Fig. 5 is an enlarged perspective view of the auxiliary clutch shifting device, the cooperating parts of the builder mechanism being shown in dotted outline.

Fig. 6 is an enlarged plan view of a portion of the auxiliary clutch shifting device appearing 10 in Fig. 5.

Fig. 7 is a transverse sectional view taken substantially along the line 7—7 of Fig. 6.

Fig. 8 is a side elevation of a latch releasing member forming part of the auxiliary clutch 15 shifting device.

Figs. 9 and 10 are views similar to Fig. 5 but showing a modified clutch shifting and timing mechanism.

Fig. 11 is a detail view of a latch appearing in 20 Figs. 9 and 10.

In these drawings the builder lever is indicated at 5. One end is pivotally mounted on a continuously rotating shaft 6 which serves as the power shaft of the wind-back motion. The other 25 end carries a roll 7 engaged by the heart-shaped builder cam 8 fixed to a continuously rotating shaft 9. The roll 7 is held to the builder cam by the weight of the spindle rails 10 and parts associated therewith. The spindle rails are connected by cross members 11 and are mounted to slide 30 on vertical guide rods 12. The cross members are suspended from shafts 13 and 14 (Fig. 1) by flexible suspension members 15 having their lower ends fastened to the cross members and their 35 upper ends fastened to winding pulleys 16. Shafts 13 and 14 are connected by chain 17 and suitable sprockets (not shown) so that rotation of shaft 13 in one direction causes shaft 14 to rotate in the opposite direction. A further 40 sprocket 18 on shaft 13 (Fig. 1) is connected by chain 19 to a sprocket 20 (Fig. 3) on transversely extending rail shifting shaft 21 carried by lever 5. A worm wheel 22 on shaft 21 is engaged by a worm 23 (Fig. 1) on a longitudinally extending worm shaft 24, also carried by lever 5.

Clutch members 26 and 27 are slidably mounted on opposite ends of the worm shaft 24. These members are grooved to receive yokes 28 fixed to opposite ends of a sliding clutch reversing shaft 29 supported in bearings 30 depending from the lever 5. A spring device, generally indicated at 31 in Figs. 1 and 2, is associated with the right hand bearing 30 to apply restraining or braking pressure to the shaft 29. As shown more particularly in Fig. 4, the spring device 31 comprises a spring casing 32 in threaded engagement with the enlarged outer end of a radial bore 33 formed in the right hand bearing 30, a ball 34 at the inner end of said bore and a spring 35 having its inner end bearing against the ball and its outer end seated in the spring casing 32. The pressure of ball 34 on the clutch reversing shaft 29 is regulated by adjusting the casing 32 to regulate the compression of the spring 35. Shaft 29 is provided with ball receiving recesses 36 and 37. When shaft 29 is in the starting position shown in Fig. 1, the ball 34 engages the recess 36 and serves to hold shaft 29 against premature or accidental shifting due to vibration or other causes. When shaft 29 is shifted from the starting to the wind-back position shown in Fig. 2 it is similarly held against accidental displacement by engagement of the ball 34 in the recess 37.

The clutch members 26 and 27 cooperate with 75 clutch members 39 and 40 fixed to the inner ends

of shafts 42 and 43 respectively mounted on lever 5 in axial alignment with shaft 24. The outer end of shaft 42 is equipped with a bevel gear 44 meshing with a similar gear 45 fixed to the shaft 6. The outer end of shaft 43 carries a ratchet 5 wheel 47 which is engaged by a driving pawl 48 (Fig. 3) and intermittently rotated in a direction opposite to rotation of the shafts 6 and 42. One end of pawl 48 is pivoted to the outer extremity of a pawl carrying arm 49 projecting from a hub 50 rotatably mounted on shaft 43. A vertical rod 51 (Fig. 1) is pivoted at its lower end to the pawl carrying arm 49. This rod extends upwardly through a suitable opening in the arm 52 of a bell crank lever 53 which is rotatably mounted 10 on the shaft 54 of the cam engaging roller 7. Collars 55 and 56 are fixed to the rod 51 above and below the arm 49 to cooperate therewith. The remaining arm 57 of the bell crank lever 53 is positioned to be periodically engaged and depressed by a stud 58 (Fig. 3) projecting from the builder cam 8. At each depression of the arm 57 the companion arm 52 is raised and acts, through the collar 55, rod 51, arm 49, and pawl 48, to effect a predetermined rotation of shaft 43. 15 When stud 58 passes out of engagement with arm 57 the pawl actuating arm 52 swings downwardly and acts, through collar 56, rod 51, and arm 49, to effect a return movement of pawl 48 to its initial position, which is determined by the 20 adjustment of a stop 59 (Fig. 2) positioned to limit the downward movement of the pawl carrying arm 49.

The shifting of the clutch reversing shaft 29 is controlled by a reversing lever 61 (Figs. 1 and 2) 35 intermediately pivoted to the builder lever 5 as indicated at 62. The lower end of lever 61 carries a stud 63 which lies between the cooperating flanges 64 and 65 of a collar 65a fixed to shaft 29. The upper end of lever 61 is disposed in the path 40 of suitable actuating lugs 66 and 67 adjustably mounted on a disk 68 fixed to shaft 21. During the winding of the bobbins the shaft 29 and lever 61 are positioned as shown in Fig. 1 so that shaft 24 is clutched to and intermittently rotated by 45 the pawl actuated feed shaft 43. The resulting intermittent rotation of shaft 21 gradually unwinds the chain 19 from sprocket 20 to effect a progressive lowering of the rails 10 in addition to the alternate raising and lowering of the rails 50 caused by the alternate raising and lowering of the cam actuated lever 5.

When the winding of the bobbins is completed the lever 61 is engaged by the lug 66 and swung from starting position shown in Fig. 1 to the 55 wind-back position shown in Fig. 2. During this operation the stud 63 at the lower end of lever 61 acts against the flange 65 to shift the shaft 29 to the wind-back position in which the shaft 24 is freed from shaft 43 and clutched to shaft 42 60 so that shaft 21 and sprocket 20 are continuously rotated in the reverse direction to restore the rails 10 to starting position. As the rails resume their starting position the machine is brought to rest by the operation of a suitable switch as described in the aforesaid United States patent.

A cam projection 70 (Figs. 1 and 2) is fixed to lever 61 to cooperate with a spring pressed plunger 71 mounted in a casing 72 secured to lever 5. The pressure of plunger 71 against the projection 70 serves to accelerate the latter part of the 70 movement of lever 61 as the latter is swung in either direction.

Before the machine is brought to rest at the completion of the wind-back operation the lever 75

61 is engaged by the lug 67 and returned to the starting position shown in Fig. 1.

In shifting lever 61 to the wind-back position, lug 66 acts against the upper end of the lever 5 until the point of the cam projection 70 passes over the point of the plunger 71. The latter then becomes effective to accelerate the movement of the lever so that the upper end of the lever travels ahead of the lug 66. It sometimes happens that the propelling force with which the lug 63 is urged against the flange 65 by the plunger 71 is insufficient to immediately overcome the restraining force exerted on shaft 29 by the spring device 31. In this event the shifting of 10 shaft 29 may be delayed until lug 66 overtakes the lever 61 and exerts further pressure thereon. The resulting delay in commencement of the wind-back motion gives rise to serious operating difficulties as previously explained.

20 The foregoing construction forms no part of the present invention except insofar as certain elements of such construction are cooperatively related to the auxiliary clutch shifting mechanism hereinafter described.

25 As here shown, the auxiliary clutch shifting device comprises an L-shaped impact member 74 (Fig. 5) presenting a vertical arm 75 terminating in a collar 76 fixed to one end of a rod 77 and a horizontal arm 78 terminating in an enlarged impact head 79 disposed in axial alignment with the right hand end of shaft 29. The rod 77 is slidably mounted in bearing blocks 80 and 81 supported by brackets 82 attached to lever 5. As shown in Figs. 1, 3 and 5, the rod 77 30 is normally held in a retracted position against the resistance of a propelling spring 83 by a latch 84 which is pivoted to the bearing block 80, as indicated at 85 (Fig. 6), and is engaged in a notch 86 formed in rod 77. The latch is yieldingly held in its operative position by a spring 87. The propelling spring 83 is arranged on rod 77 with one end engaging the bearing block 80 and the other end engaging an abutment 88 fixed to the left hand end of the rod.

45 The free end of latch 84 rests on a latch releasing member 89 slidably mounted in a slot 90 formed in the bearing block 80. The latch releasing member 89 is connected to the reversing lever 61 by the eye-bolt connection 91 (Fig. 8) 50 and is provided with a cam projection 92 which serves to lift the latch 84 clear of the notch 86 when the lever 61 is moved by the lug 66 to a position where the point of the lever cam 70 has passed over the point of the spring pressed 55 plunger 71. When this occurs the spring 83, which is normally compressed, becomes effective to propel the rod 77 and the impact member 74 from the position shown in Fig. 1 to the position shown in Fig. 2. The impact head 79 is 60 thus driven against the adjacent end of shaft 29 with sufficient force to overcome the resistance of the spring restraining device 31 and effect immediate shifting of the shaft to the wind-back position. Since the propelling force 65 of the spring actuated impact member 74 is greatly in excess of the restraining force of the spring device 31 no serious consequences follow when the latter is accidentally adjusted to apply a restraining pressure greater than that actually required to prevent accidental displacement of shaft 29 due to vibration or the like.

70 When lever 61 and latch releasing member 89 are automatically returned to starting position upon completion of the wind-back motion 75 the rod 77 and impact member may be reset

by hand or automatically. In the present instance I have shown automatic resetting mechanism including a resetting handle 94 pivoted, at 95, to a plate 96 adjustably secured to a lug 97 on the collar 76 of the impact member 74. 5 A coiled spring 98 is connected between the handle 94 and a post 99 rising from the bearing block 81. When the rod 77 is in its retracted position the handle 94 is swung forwardly by the pull of the spring 98 and lies in an inclined 10 position against the lug 97 as shown in Fig. 5. In this position the handle is cleared by a crank extension 101 fastened to the stud 58 of the builder cam 8.

15 A small rod 102 is arranged within the coiled spring 98 with one end pivotally attached to the handle 94. When the handle 94 is in the position shown in Fig. 1 the opposite or free end of rod 102 is spaced from the post 99. When the rod 77 and impact member 74 are released 20 and shifted to the position shown in Fig. 2 the free end of rod 102 engages the post 99 at a suitable instance before the rod 77 reaches the end of its clutch reversing travel. As the handle continues to travel with the rod 77 the pressure 25 of the rod 102 serves to swing the handle to the more or less upright position as shown in Fig. 2. The handle is thus disposed to be engaged and returned to its starting position by the crank extension 101 as the latter makes a complete 30 anti-clockwise revolution, from the position shown in Fig. 1. During the resetting operation the handle is held upright by the pressure of the crank extension 101 until it reaches the dotted line position shown in Fig. 2. At this time the 35 crank extension leaves the resetting handle and permits it to resume the inclined position shown in Fig. 1. When engaged by the crank extension 101 the handle is prevented from swinging too far to the right by a stop 104 (Fig. 5) carried by the plate 96 in suitable proximity to the lower end of the handle.

40 In Figs. 9 and 10 I have shown a second restraining latch for the clutch shifting mechanism which serves as a timing device to prevent shifting of the clutches to the wind-back position until the cam reaches a predetermined position in relation to the cam engaging roller of the builder lever. In this case a second latch assembly, generally indicated at 105, is associated with the reversing lever 61 and serves as a timing device which prevents releasement of the latch 84 until the cam 8 reaches a position where the lowest point L of the cam is passing over the roller 7, as shown in Fig. 10. In this position of the cam the worm shaft 43 is at rest since the stud 53 is moving toward but has not yet engaged the pawl actuating arm 57. When the shifting of the clutches to the wind-back position is timed to occur at the instant when the lowest point L of the cam is passing over the roller 7 the cam will come to rest at the completion of the wind-back operation with the highest point P of the cam engaging the roller 7 so that, when the machine is again started up, the 55 initial movement of the builder lever in response to rotation of the cam will be in an upward or 60 downward direction.

65 The latch assembly 106 comprises a horizontally slideable latch member 106 working between 70 side walls 107 and 108 rising from the bearing block 81. The ends of said walls nearest to the lever 61 are connected by a transverse wall 109 provided with a slot 110 for the passage of the latch 106. One end of latch 106 is connected 75

to lever 61 by an eye bolt connection 106a. Adjacent its opposite end, latch 106 is provided with a downwardly facing notch 111 (Fig. 11) affording a stop shoulder 112 opposed to a transversely extending latch retaining member 113 working in downwardly opening slots 114 formed in the walls 107 and 108. One end of the latch retaining member 113 is mounted on a pivot 113a carried by the wall 107 and is normally held in the raised position shown in Fig. 9 by a suitable spring 115. The other end of member 113 projects beyond the wall 108 and lies beneath the horizontal arm 116 of an L-shaped rod 117 having its vertical arm 118 fastened to a bracket 119 which extends outwardly over the builder lever 5 from a suitable portion 120 (Fig. 9) of the machine frame. The latch 106 is normally positioned so that its shoulder 112 is spaced a slight distance from the opposing surface of the latch retaining member 113.

The operation of the latch assembly 106 will be clear from the following description: When the lever 61 is moved by the lug 66 to a position where the point of the cam projection 70 has just passed over the point of the spring pressed plunger 71, the latch member 106 is moved to the right by the eye bolt connection 110 so that the shoulder 112 is jammed against the opposing surface of the latch retaining member 113 as shown in Fig. 9. This engagement of the shoulder 112 with the latch retaining member 113 occurs before the lever 61 has moved a sufficient distance to release the latch 84. The latch 106 therefore serves to prevent release of the latch 84 until the cam reaches the position shown in Fig. 10. As the cam reaches this position the upward movement of the builder lever 5 causes the free end of the latch retaining member 113 to engage and be depressed by the lower arm 116 of the rod 117. The latch retaining member 113 is depressed sufficiently by engagement with the arm 116 so that its upper edge is moved downwardly clear of the shoulder 112. The latch member 106 is then free to travel to the right to permit release of the latch 84 by the lever 61.

Having set forth the principles of the invention, together with a preferred embodiment, I reserve the right to such modifications as fall within the scope and spirit of the invention as defined by the appended claims.

Having thus described my invention, what I claim is:

1. In a builder mechanism for spinning frames comprising a builder lever, a builder cam, a rail-shifting shaft rotatably mounted thereon, rail-shifting connections functioning to progressively lower a rail of the machine in response to rotation of the shaft in one direction and to return the rail to starting position in response to rotation of the shaft in the reverse direction, means for intermittently rotating said shaft in a rail-lowering direction during the winding of the bobbins, means for continuously rotating the shaft in the reverse direction after the winding of the bobbins is completed, alternately operative clutch members shiftable to a starting position to establish a driving connection between said shaft and said first-mentioned means or to a wind-back position to establish driving connection between said shaft and said second means, an automatically operated clutch-reversing element, and means to cause said element to shift the clutch members to the wind-back position when the winding of the bobbins has proceeded for a predetermined period, that im-

provement which consists in providing an auxiliary impact member effective to exert an abrupt supplemental propelling force directly and axially on said clutch-reversing element, and means coacting with said builder mechanism to determine the point in the cycle of building operation at which said impact member becomes operative.

2. In a builder mechanism for spinning frames comprising a builder lever, a builder cam, a rail-shifting shaft rotatably mounted thereon, rail-shifting connections functioning to progressively lower a rail of the machine in response to rotation of the shaft in one direction and to return the rail to starting position in response to rotation of the shaft in the reverse direction, means for intermittently rotating said shaft in a rail-lowering direction during the winding of the bobbins, means for continuously rotating the shaft in the reverse direction after the winding of the bobbins is completed, alternately operative clutch members shiftable to a starting position to establish a driving connection between said shaft and said first-mentioned means or to a wind-back position to establish driving connection between said shaft and said second means, an automatically operated clutch-reversing element, and means to cause said element to shift the clutch members to the wind-back position when the winding of the bobbins has proceeded for a predetermined period, that improvement which consists in providing an auxiliary impact member effective to exert an abrupt supplemental propelling force directly and axially on said clutch-reversing element, and means coacting with a fixed abutment on said spinning frame to release said impact member as said builder lever is engaged by the low point of the builder cam.

3. In a builder mechanism for spinning frames comprising a builder lever, a builder cam, a rail-shifting shaft rotatably mounted thereon, rail-shifting connections functioning to progressively lower a rail of the machine in response to rotation of the shaft in one direction and to return the rail to starting position in response to rotation of the shaft in the reverse direction, means for intermittently rotating said shaft in a rail-lowering direction during the winding of the bobbins, means for continuously rotating the shaft in the reverse direction after the winding of the bobbins is completed, alternately operative clutch members shiftable to a starting position to establish a driving connection between said shaft and said first-mentioned means or to a wind-back position to establish driving connection between said shaft and said second means, an automatically operated clutch-reversing element, and means to cause said element to shift the clutch members to the wind-back position when the winding of the bobbins has proceeded for a predetermined period, that improvement which consists in providing a separate and additional impact member adapted to deliver a sharp blow against the clutch-reversing element to assist in shifting the clutch member to the wind-back position, a propelling spring effective to give said impact member an operative movement, a latch normally holding said impact member in a retracted position against the force of said spring, and automatic means coacting with said builder mechanism to release said impact member at a predetermined point in the cycle of building operation.

4. In a builder mechanism for spinning frames

comprising a builder lever, a builder cam, a rail-shifting shaft rotatably mounted thereon, rail-shifting connections functioning to progressively lower a rail of the machine in response to rotation of the shaft in one direction and to return the rail to starting position in response to rotation of the shaft in the reverse direction, means for intermittently rotating said shaft in a rail-lowering direction during the winding of the bobbins, means for continuously rotating the shaft in the reverse direction after the winding of the bobbins is completed, alternately operative clutch members shiftable to a starting position to establish a driving connection between said shaft and said first-mentioned means or to a wind-back position to establish driving connection between said shaft and said second means, an automatic clutch-reversing element, and means to cause said element to shift the clutch members to the wind-back position when the winding of the bobbins has proceeded for a predetermined period, that improvement which consists in providing an auxiliary impact member effective to exert an abrupt supplemental propelling force directly and axially on said clutch-reversing element, and means coacting with said builder mechanism to release said impact member at a point in the cycle of building operation at which the intermittent feed of the rail-shifting shaft is inoperative.

5. In a builder mechanism for spinning frames comprising a builder lever, a builder cam, a rail-shifting shaft rotatably mounted thereon, rail-shifting connections functioning to progressively lower a rail of the machine in response to rotation of the shaft in one direction and to return the rail to starting position in response to rotation of the shaft in the reverse direction, means for intermittently rotating said shaft in a rail-lowering direction during the winding of the bobbins, means for continuously rotating the shaft in the reverse direction after the winding of the bobbins is completed, alternately operative clutch members shiftable to a starting position to establish a driving connection between said shaft and said first-mentioned means or to a wind-back position to establish a driving connection between said shaft and said second means, an automatic clutch-reversing element, and means to cause said element to shift the clutch members to the wind-back position when the winding of the bobbins has proceeded for a predetermined period, that improvement which consists in providing an auxiliary impact member effective to exert an abrupt supplemental propelling force directly and axially on said clutch-reversing element, and means coacting with said builder mechanism to release said impact member at a point in the cycle of building operation at which the intermittent feed of the rail-shifting shaft is inoperative and the low point of the builder cam is in engagement with the builder lever.

LIONEL DESROSIERS.
